FIG. 1

FIG. 2

FIG. 3

INVENTOR.
A. H. Daelein

BY
Alfred J. Ford
ATTORNEY

UNITED STATES PATENT OFFICE.

ALF H. DAEHLIN, OF WOODFORD, WISCONSIN.

HAY LOADER.

1,413,009.

Specification of Letters Patent. Patented Apr. 18, 1922.

Application filed August 20, 1919. Serial No. 318,735.

To all whom it may concern:

Be it known that I, ALF H. DAEHLIN, a citizen of the United States, residing at Woodford, in the county of Lafayette and 5 State of Wisconsin, have invented certain new and useful Improvements in Hay Loaders, of which the following is a specification.

My said invention relates to a shield for 10 hay loaders, and the object of the same is to provide a device of this sort which shall prevent side winds from blowing the hay off the wagon as it is elevated by the loader. Such a shield may be provided either on a loader 15 of the type that discharges at the forward upper end or on a loader of the type that discharges at the rear upper end. I have not shown specific features of either type as both are common and well known to those skilled 20 in the art. In haying time stiff breezes are of common occurrence and the dry hay is often very light, greatly increasing the work of the man on the wagon and causing duplication of work and loss of hay. By the use 25 of my device such duplication and loss are prevented as the shield stands at the side of the stream of hay where it is discharged from the loader, and prevents the wind from carrying it over the side of the basket rack 30 such as is ordinarily used with a hay loader.

Referring to the accompanying drawings which are made a part hereof and on which similar reference characters indicate similar parts,

35 Figure 1 is a side elevation of my device in working position on a hay-loader, of which only so much is shown as is deemed necessary for full disclosure of the invention.

40 Figure 2 is a section on line 2—2 of Figure 1, and

Figure 3 is a detail of a part of a holding device.

In the drawings, reference character 1 denotes a part of the side frame of the loader forming a guideway for the downwardly moving run of the usual conveyor, and having an angular extension 1^a forming a guideway for the upward run of the conveyor. 45 Brackets 2 and 3 are provided on the parts 1 and 1^a respectively, and these brackets are secured in position to bring the lower edge of the gate slightly above the upper edge of the basket' rack. As indicated by dotted 50 lines in Figure 1, the rear parts of jointed brackets 2 and 3 may be set at various an-

gles to the front parts 22 to meet the exigencies of the situation in loaders of various types, since in some loaders it will be feasible to fasten the brackets in one position, while in others a different position will be preferable. The horizontal position of the shield may also be varied in this way if necessary or desirable.

An adjustable joint of known type is provided between the parts of each bracket at 10, each member having alternate radiating ribs 12 and depressions 11, as shown in Figure 3, and being held in adjusted position by a bolt 21.

The forward part of each bracket 2 and 3 consists of a member 22 which may have a single projection with a corrugated face to contact with a similar face on a projection of a member 25, similarly to the joint at 10 75 or the member 22 may be forked and each inner face may engage a similar face on a projection of a member 25. In either case a bolt 23 holds the parts in place resiliently due to a spring on the bolt exerting pressure 80 on the joint. By swinging members 25 in or out, the shield may be moved bodily on bolts 23 as pivots to adapt it to racks of greater or less width.

Each bracket member 25 is split at its forward side to provide a clamp for a rod or tube 4 and bolts 26 hold the parts in clamping position about the same.

The rod is provided with pins 19 passing through it and rotary hinges 16 are supported on said rod, said hinges having notches at 18 adapted to lock the shield against swinging movement unless it is first lifted to clear the notches of the pins.

The shield has horizontal members 6, 6 95 8, 8 pivotally attached to a pair of vertical members 5 and 7 at 9, 9. The rear member 5 to which hinges 16 are secured supports the shield adjustably by means of ribbed parts 10' on said member and on the members 8, 8. Bolts 17 pass through the ribbed parts 10' and act as pivots therefor, the bolts being surrounded by springs 15 which hold the parts in adjusted position. Nuts 14 serve to secure the bolts in place and to adjust the 100 tension of the springs. The parts 6, 6, 8, 8 and 7 may thus swing up and down as in parallel link motions, to adapt the shield to racks of varying height.

It will be obvious that a shield may be 110 placed at each side of the loader and in fact this will be the ordinary structure. My de-

vice may also be modified in various other ways without departing from the spirit of the invention, the true scope of which is shown in the appended claims.

5 Having thus fully described my said invention, what I claim as new and desire to secure by Letters Patent, is:

1. In a hay loader, means for preventing loss of hay comprising a shield and means 10 for holding said shield in operative or inoperative position at the upper end of the loader, substantially as set forth.
2. In a hay loader, means for preventing loss of hay comprising a shield mounted at 15 each side of the loader and adapted to be moved into active position or to inactive position alongside the loader, and individual means for holding each shield in each of said positions, substantially as set forth.
- 20 3. In a hay loader, means for preventing loss of hay comprising a shield mounted at the side of the loader at the discharge end, and normally projecting in the direction of discharge, means supporting the shield for 25 movement about a vertical pivot whereby it may be adjusted bodily in a direction transversely of the loader and means for holding it in its adjusted position, substantially as set forth.
- 30 4. In a hay loader, means for preventing loss of hay comprising a shield having a series of parallel normally horizontal members, a common support to which they are loosely pivoted at one end to provide for 35 simultaneous angular adjustment of said members, and yieldable means to hold them in adjusted position, substantially as set forth.
- 40 5. In a hay loader, means for preventing loss of hay comprising a shield and means

for supporting the shield on the side of the loader including a pair of brackets, and rearwardly projecting members thereon pivotally mounted for movement in a vertical plane, and adapted to be fixed to the sides of 45 the loader in adjusted position, substantially as set forth.

6. In a hay loader, a shield adapted to project in the direction of discharge, a vertical pivot on the loader, a hinge on the shield 50 having a notch and oppositely projecting pins on the pivot adapted to engage in said notch to hold the shield respectively in active and inactive position, substantially as set forth.

55 7. In a hay loader, a shield mounted on the loader and projecting in the direction of discharge, and supporting means for said shield permitting bodily movement transversely of the loader, vertical angular adjustment and movement into inactive position alongside the loader, substantially as set forth.

8. In a hay loader, a hay shield, means supporting the shield at the side of the 60 loader for movement about a vertical axis into operative and inoperative positions, means to hold it in either of such positions, means supporting it for adjustment about a second vertical axis and means to hold it in 65 any of its adjusted positions, substantially as set forth.

In witness whereof I have hereunto set my hand and seal at Woodford, Wisconsin, this 16th day of August, A. D. nineteen 70 hundred and nineteen.

ALF H. DAEHLIN. [L.S.]
